John C. Lyon

UNITED STATES PATENT OFFICE.

JOHN C. LYON, OF EAST ORANGE, NEW JERSEY, ASSIGNOR TO J. M.
LITTELL & CO.

DESIGN FOR A CAKE OF SOAP.

Specification forming part of Design No. **11,410**, dated September 9, 1879; application filed July 24, 1879.
[Term of patent 3½ years.]

To all whom it may concern:

Be it known that I, JOHN C. LYON, of East Orange, in the county of Essex and State of New Jersey, have invented and designed a novel Configuration for a Cake of Soap, of which the following is a full, clear, and exact description, reference being had to the accompanying drawing, making a part of this specification.

The nature of my design is fully illustrated in the accompanying drawing, to which reference is made.

The nature of my invention consists in molding or otherwise forming a cake of soap having the general outline of a horseshoe, with a face in the center thereof. I usually make the horseshoe of one color and the face of another;

but I do not propose to limit myself as to the matter of colors, the main feature of my design being a cake of soap having the configuration of a horseshoe with a face in the center of the same. I also sometimes stamp the words "Good Luck" on the face of the horseshoe; but this I do not deem essential.

Having thus fully described the nature and character of my design, what I claim as my invention is—

A design for a cake of soap, consisting of the figure of a face surrounded by a horseshoe, as shown and described.

JOHN C. LYON.
